Primary Examiner — Ian Simmons*Assistant Examiner* — Keith Frank(74) *Attorney, Agent, or Firm* — Adam K. Sacharoff; Much Shelist, P.C.(57) **CLAIM**

The ornamental design for a ribbed container, as shown and described.

DESCRIPTION

FIG. 1 is a front side perspective view of a ribbed container showing our new design;

FIG. 2 is a rear side perspective view thereof;

FIG. 3 is a front rear side perspective view in an upside down configuration thereof;

FIG. 4 is a front elevation view thereof,;

FIG. 5 is a rear elevation view thereof;

FIG. 6 is a left side view thereof;

FIG. 7 is a right side view thereof;

FIG. 8 is a top plan view thereof; and,

FIG. 9 is a bottom plan view thereof.

The broken lines in the drawings showing the ribbed container illustrate the portions of the ribbed container that form no part of the claimed design.

1 Claim, 9 Drawing Sheets(56)
